TUNING INDICATOR SYSTEM

John D. Reid, Philadelphia, Pa., assignor to Radio Corporation of America, a corporation of Delaware

Application October 26, 1940, Serial No. 362,910

10 Claims. (Cl. 250—40)

This invention relates to tuning indicator systems for radio signal receiving apparatus and the like, and has for its primary object to provide an improved tuning indicator system for frequency modulation signal receiving systems which is adapted to be connected with a balanced frequency modulation detector to indicate accurately the tuning of said system to resonance with a received signal.

It is a further object of this invention to provide a system for deriving from a frequency modulation balanced detector circuit two control potentials which vary in the same sense and at differing rates when tuning through the center frequency of a received signal, the potential difference being maximum at resonance with said center frequency.

It is also a further object of this invention to provide a system for deriving a resultant variable control voltage from the aforesaid potentials, which control voltage has a relatively sharp peak corresponding to resonance or balanced tuning, whereby such voltage may be used for tuning indication and the like.

The invention will further be understood from the following description when considered in connection with the accompanying drawing, and its scope is pointed out in the appended claims.

In the drawing:

Figure 1 is a schematic circuit diagram of a frequency modulation detector provided with a tuning indicator system embodying the invention.

Figures 2, 3 and 4 are graphs showing curves illustrating certain operating characteristics of the circuit of Fig. 1, and

Figure 5 is a schematic circuit diagram of a portion of the circuit of Fig. 1 showing a modification of the tuning indicator means.

Referring to Fig. 1, a frequency modulation detector comprising a pair of diode rectifiers 6 and 7 are connected in balanced relation with an output resistor network 8 and 9 and with an input circuit 10 forming part of a frequency discriminator network 11 coupled to the output circuit 12 of a preceding amplifier stage 13, which may be the final stage of an intermediate frequency amplifier.

As is well known, the output characteristic of a frequency discriminator network and rectifier forming a frequency modulation detector, as in the present example, may be represented as shown in Fig. 2 by the curve E2, this voltage appearing across the output terminals 15 and 16 of the output resistor network. At resonance

with the center frequency F_0 , the output voltage across the terminals 15—16 is zero, as indicated in Fig. 2.

The output voltage $E1$ across one-half of the resistor network, such as across the resistor 9, varies in accordance with the curve $E1$ in Fig. 2, for variations in frequency about resonance. If a rectifier 17 is provided, as shown, in connection with the terminal 15 and in series with an output impedance or resistor 18 to the terminal 16, a second variable negative voltage $E2a$ will be provided, as indicated by the heavy line curve in the negative half of the curve $E2$. The system thus provides two negative voltages $E1$ and $E2a$ which vary in the same sense and at differing rates and provide a maximum difference at resonance or balanced tuning at the frequency F_0 . The rectifier 17 is poled so that $E2a$ is of like sign with $E1$ in any case.

The potential $E1$ is derived from the output network of the detector across an output resistor 19 which is connected to the resistor 9 through a filter network comprising a series resistor 20 and a bypass capacitor 21. In the same manner, the rectifier 17 is connected across the entire output network of the detector through a filter network comprising a series resistor 22 and a bypass capacitor 23, such filters being provided to reduce the audio frequency component appearing across the output circuit 15—16. Both resistors 18 and 19 are connected to the low potential terminal 16 of the network which is also connected to ground, as indicated at 24. The output resistor 18 is further provided with a bypass capacitor 25.

It is obvious that the positive half of the voltage output characteristic $E2$ of the detector may be utilized in a similar manner for deriving two positive voltages which vary in the same sense and at differing rates with variation of tuning or frequency about resonance, although the arrangement shown is at present preferred for the reason that the cathodes of the rectifiers may be operated at low R. F. potential.

As will be seen from Fig. 2, the voltages $E1$ and $E2a$ appearing at terminals 30 and 31 of the output resistors 18 and 19 vary at different rates as the receiving system is tuned through a signal. The difference between $E1$ and $E2a$ is greatest at the center frequency F_0 , as indicated at E_{max} , which is the desired point for correct tuning.

As a means for utilizing the divergent voltages at resonance for effecting a tuning indication or control voltage having a peak corre-

sponding to resonance, an amplifier tube 35 is provided in connection with resistors 18 and 19, for differential response to said voltages. For this purpose, the tube is provided with a pair of control grids 36 and 37 located between the cathode 38 and the main anode 39 have positive and negative mutual conductance characteristics with respect to a third grid or electrode 40 interposed between them so that as a biasing or control potential applied to the grid 36, which may be indicated as g_1 , is varied in a negative direction, the current to the electrode 40 or g_2 , when energized positively with respect to the cathode, is decreased, as indicated in Fig. 3 by the curve 41, the current to the electrode 40 being indicated along the ordinate Ig_2 .

The mutual conductance of the grid 37 or g_3 with respect to the electrode 40 is negative, and the variation in current to the electrode 40 with an increase in the negative biasing potential applied to the grid 37 is indicated by the curve 43 in Fig. 3. The arrangement is such that, with predetermined negative biasing potentials applied to the two grids, equal variations in the values of said potentials in the same sense or direction provides substantially constant current, Ig_2 , on the electrode 40.

If the voltages applied to the control grids g_1 and g_3 , that is, the electrodes 36 and 37, are varied at differing rates but in the same sense or direction, then the current to the auxiliary electrode 40 or g_3 will reach a maximum or minimum value, depending upon which one of the control grids is higher in voltage, when the difference between the applied voltages is maximum, as at resonance in the present example.

The curve 45 in Fig. 4 shows the effect of applying the voltages E_1 and E_{2a} to the grids 36 and 37, respectively. It will be noted that the current to the auxiliary electrode 40 drops to a relatively sharp peak 46 at the resonance or center frequency F_0 . By reversing the connections to the grids 36 and 37, the peak may be extended in a positive direction, as indicated at 47. In either case, a relatively sharp change in current to the electrode 40 is provided at resonance.

This change in current is utilized in any suitable manner for controlling an indicating device or other apparatus in connection with the receiving system and, in the present example, is translated into voltage variation through the medium of the output resistor 48 connected in circuit between the electrode 40 and a source of positive anode potential provided by the supply lead indicated at 49, the ground or negative return lead for which is indicated at 50.

The resistor 48 is suitably bypassed as indicated at 51 and the anode or high potential terminal of the resistor 48 is connected to a control electrode 53 in a tuning indicator tube 54. The latter may be provided with the usual cathode 55, and target electrode 56, which fluoresces when connected to a positive source of current such as the lead 49 over that portion which is not shadowed by the control electrode 53. A tube of this character is known commercially as an RCA 6AF6G. The main anode electrode 39 of the tube 35 is connected also to the positive potential supply source 49.

The variation in anode current to the electrode 40 when tuning through resonance is applied in the form of voltage variation to the control electrode 53 of the tuning indicator tube 54 across the resistor 48. Since this tuning

characteristic has a relatively sharp peak, exact resonance is readily indicated. Any other suitable tuning indicating device, however, may be provided in connection with the output circuit 5 from the electrode 40. For example, a modification of the tuning indicating means may be provided as shown in Fig. 5, in which the same reference numerals are applied to like circuits and circuit elements as in Fig. 1.

Referring to Fig. 5, the rectifier 17 is provided to derive a second variable potential responsive to variations in frequency in the same sense as the potential derived from one-half of the output impedance network 8-9 of the discriminator and detector circuit, whereby, at resonance to the center frequency, the potentials have a maximum difference as shown in Fig. 2 and as hereinbefore described.

Likewise, the tube 35 is provided in which the two control electrodes 36 and 37 connected with the output terminals 30 and 31 of the resistors 18 and 19 have positive and negative mutual conductance characteristics with respect to the output electrode 40. The latter is connected through the potential drop producing resistor 48 which is utilized to couple the electrode 40 to the control grid 58 of an amplifier tube 59, whereby a relay device 60 in the output anode circuit 61 is actuated in response to the peak 46 or 47 of Fig. 4 as the tuning passes through resonance.

In the present example, operation of the relay 60 causes a pair of contacts 62 to open, thereby permitting signal output from the receiving system. The contacts are connected across the output circuit 63 for the loudspeaker 64 which, in turn, is supplied with signals from the detector through a suitable audio frequency amplifier 65 and a connection 66 including a coupling capacity 67 to the high potential terminal 15 of the output network 8-9.

With this arrangement, exact resonance to a received signal is indicated by operation of the loudspeaker device, while at all other times the receiving system is silent. Any other suitable control circuit may, however, be provided in connection with the output circuit of the tube 59.

I claim as my invention:

1. In a frequency modulation signal receiving system, the combination of a frequency discriminator network, means for applying variable frequency signals thereto, rectifier means connected with said network providing a balanced output circuit, and means for deriving from said output circuit two voltages which vary in the same sense and at differing rates in response to signal frequency variation causing a divergence which maximizes in response to a predetermined signal frequency.

2. In a frequency modulation signal receiving system, the combination of a frequency discriminator network, means for applying variable frequency signals thereto, rectifier means connected with said network providing a balanced output circuit, means for deriving from said output circuit two voltages which vary in the same sense and at differing rates in response to signal frequency variation causing a divergence which maximizes in response to a predetermined signal frequency, a control tube having control electrodes connected with said last-named means and an output electrode, and means providing a current variation through said output electrode having a relatively sharp

peak in response to said maximum potential divergence.

3. In a frequency modulation signal receiving system, the combination of a frequency discriminator network, means for applying variable frequency signals thereto, rectifier means connected with said network providing a balanced output circuit, means for deriving from said output circuit two voltages which vary in the same sense and at differing rates in response to signal frequency variation, and means for indicating a maximum difference between said voltages as an indication of resonance at a predetermined signal frequency.

4. In a frequency modulation signal receiving system, the combination of a frequency discriminator network, rectifier means connected with said network providing a balanced output circuit, an output impedance connected across one-half of said balanced output circuit, a second output impedance connected across said output circuit including a series connected rectifier device, and means for deriving from said output impedances two signal-responsive variable control potentials which vary in the same sense and at different rates providing a maximum potential difference at a predetermined center frequency.

5. The combination of a frequency discriminator network, means for applying variable frequency signals thereto, rectifier means connected with said network providing a balanced output circuit, an output impedance connected across one-half of said balanced output circuit, a second output impedance connected across said output circuit including a series-connected rectifier device, and means for deriving from said output impedances two voltages which vary in the same sense and at differing rates with variation in frequency of a signal applied to said network, and means for indicating a maximum difference between said voltages to provide an indication of resonance at a predetermined mean frequency.

6. In a frequency modulation signal-receiving system, the combination of a frequency discriminator network, signal rectifier means comprising a pair of rectifier devices connected in balanced relation with said network, means providing a balanced output circuit for said rectifier devices, means for deriving from said output circuit two signal-responsive variable control potentials which vary in the same sense and at different rates providing a maximum potential difference at a predetermined center frequency, and means responsive to said maximum potential difference for indicating resonance to said predetermined center frequency.

7. In a frequency modulation signal-receiving system, the combination of a frequency discriminator network, rectifier means comprising a pair of rectifier devices connected in balanced relation with said network, means providing a balanced

output circuit for said rectifiers, means for deriving from said output circuit two signal-responsive variable control potentials which vary in the same sense and at different rates providing a maximum potential difference at a predetermined center frequency, and current-controlling means differentially responsive to said potentials for effecting a current change having a peak in response to said maximum potential difference.

10 8. In a frequency modulation signal-receiving system, the combination of a frequency discriminator network, rectifier means comprising a pair of rectifier devices connected in balanced relation with said network, means providing a balanced output circuit for said rectifiers, means for deriving from said output circuit two signal-responsive variable control potentials which vary in the same sense and at different rates providing a maximum potential difference at a predetermined center frequency, a tube having two control grids connected with said last-named means for differential response to said output potentials and having an output electrode, an output impedance in circuit with said output electrode, and means for utilizing potential variations therein.

15 9. In a frequency modulation signal-receiving system, the combination of a frequency discriminator network, balanced signal rectifier means connected with said network, means providing a balanced output circuit for said rectifier means, means for deriving from said output circuit two signal-responsive variable control potentials which vary in the same sense and at differing rates providing a maximum potential difference at a predetermined resonance frequency, a tube having two control grids each connected to said output circuit and having an output electrode providing positive and negative mutual conductance with respect to said control grids with variation in potential on said grids in the same sense, an output impedance in circuit with said output electrode, and a tuning indicating means connected with said output impedance.

20 10. The combination of a frequency discriminator network, rectifier means connected with said network providing a balanced output circuit, an output impedance connected across one-half of said balanced output circuit, means providing a filter in said connection, a second output impedance connected across said output circuit including a series-connected rectifier device, means providing a filter in said last-named connection, means for deriving from said output impedances two signal-responsive variable control potentials which vary in the same sense and at differing rates providing a maximum potential difference at a predetermined frequency, and means responsive to said maximum potential difference for indicating a condition of resonance to a signal applied to said network.

JOHN D. REID.
